DESIGN FOR A FINGER RING

Harry Dreyer and Max Gottlieb, New York, N. Y.

Application June 4, 1942, Serial No. 107,097

Term of patent 7 years

To all whom it may concern:

Be it known that we, Harry Dreyer and Max Gottlieb, citizens of the United States of America and residents of the county of Kings, city and State of New York, have invented a new, original, and ornamental Design for a Finger Ring, of which the following is a specification, reference being had to the accompanying drawing, forming a part thereof.

Figure 1 is a plan view of a finger ring showing our new design.

Figure 2 is a side view of this ring.

Figure 3 is a side view of one shank of this ring.

Figure 4 is a side view of the other side of the ring.

We claim:

The ornamental design for a finger ring, substantially as shown.

HARRY DREYER.
MAX GOTTLIEB.
